DRY SHAVER

James H. Rand, Jr., Stamford, Conn., and Wallace H. Nichols, Port Washington, N. Y., assignors, by mesne assignments, to Remington Rand Inc., Buffalo, N. Y., a corporation of Delaware

Application March 31, 1938, Serial No. 199,134

3 Claims. (CL 38—43)

This invention relates to improvements in dry shavers and more particularly to a type of razor having a vibrating motor for operating the shaving head.

Heretofore razors having a vibrator motor for oscillating the inner cutter of the shearing head have been noisy and created considerable undesirable vibration in the hands of the operator. This has been found to be due to the armature striking the core of the magnet, the sides of the casing, and also the free movement sets up a vibration due to the inertia of the arm.

Therefore, the principal object of the invention is to provide a cushion or yielding stop, of sound deadening material such as rubber, in the base of the shearing head to absorb the shock and resiliently limit the stroke of the actuating arm engaging the inner cutter thereby tending to silence the razor.

Another object is to provide a resilient stop which will accelerate the reversal of movement of an oscillating arm.

A further object of the invention is to provide a satisfactory dry shaver that may be manufactured with less precision at a minimum cost.

Other and additional objects, together with the construction, combination, arrangement and relative location of the parts embodying the invention will be disclosed in the following specification taken in connection with the accompanying drawing in which:

Fig. 1 is an elevational view of the device embodying our invention with parts of the casing broken away to reveal the motor.

Fig. 2 is an enlarged top view of the device shown in Fig. 1.

Fig. 3 is a cross sectional view taken along line 3—3 of Fig. 2.

Fig. 4 is a view of the base of the shearing head of our device taken substantially along line 4—4 of Fig. 3, revealing a sound deadening cushion to absorb the shock of the actuating arm of the armature, and

Fig. 5 is a view similar to that shown in Fig. 4 disclosing modified means to absorb the shock of the actuating arm of the armature.

Like characters of references refer to like parts in all the figures of the drawing.

Referring more particularly to Fig. 1 the device embodying the invention is contained in a suitable casing 10 which forms a grip handle for the shaver. Part of casing 10 is broken away and reveals a solenoid or vibrator type of a motor 11. Removably secured to casing 10 by set screw 55

12 is a shearing head 13 comprising a fixed outer cutter 14 and an inner cutter 15.

Motor 11 is a durable effective type, inexpensive to construct and assemble. A laminated iron core 16 is secured to casing 10 by screws 17. A coil 18 is secured to the core 16 by a sheet metal clip 19. The coil 18 and core 16 form a type of well known A. C. magnet adapted for use only with alternating current which is supplied over wires 20. The core 16 is magnetized twice for each cycle of current, thus if a sixty cycle current is used the core will be magnetized one hundred and twenty times per second.

It is well known that the addition of a set of interrupter contacts will adapt this type of vibrator for use with either A. C. or D. C. current. A bracket 21 is secured by screws 22 to a seat in the base of casing 10. An upright armature 23 of laminated plates is secured at its lower end to bracket 21. To the upper end of armature 23 is fastened an actuating arm 24. A pair of resilient plungers 25 are shown having their ends seated in a plate 26 which also has a cut-out portion to permit clearance for arm 24. Arm 24 and resilient plungers 25 extend through apertures 27 and 28, respectively, at top of casing 10 and engage the inner cutter 15. The arm 24 engages a slot therein to oscillate the cutter and, plungers 25 force the cutter bars of the inner cutter into shearing engagement with the cutter bars of the outer cutter. Access to motor 11 may be had by removing the three screws 29 in a cover plate secured to one side of casing 10.

Outer cutter 14 has apertures 30 and 31 through which arm 24 and plungers 25 respectively extend. Aperture 30 as shown in Fig. 4 is elongated to permit a yielding stop 32 of noise deadening material, preferably rubber for the arm 24, to be firmly positioned therein.

Cushion 32 has an opening 33 therein of sufficient size to permit arm 24 to move freely but limit the amplitude of oscillation near its ends. Fig. 5 discloses a modification of the stop element in the form of two rubber plugs 34 which fit snugly into enlarged ends of aperture 30. These stops form resilient means for limiting the oscillation of the arm 24 and, due to the quick returning action at the end of each stroke, the average velocity of the inner cutter is raised. It is obvious that cushion 32 may be secured on the actuating arm 24 in place of being positioned in the aperture 30.

The outer cutter 14 is provided with slots 35 which are positioned diagonally to the longitudinal axis of the cutter. These slots form

cutter bars 36. The slots extend down the wall of the outer cutter forming comb members which are adapted to comb up any long hairs and conduct them to the diagonal shearing edges.

The inner cutter 15 is provided with transverse slots 38, positioned at right angles to the longitudinal axis of the cutter, which form cutter bars 39.

In operation the motor 11 oscillates the inner cutter at a high rate of speed thereby cutting each hair at least twice during the travel of the razor over the face. In the case of long hairs such as side burns the comb members mentioned above draw the hair into the shearing surfaces where it is cut short and then it snaps into the next slot where it is cut again before the razor has passed on. Simultaneously with the above action the entire razor is vibrating parallel to the longitudinal axis of the cutter or at right angles to the line of the travel of the cutter over the face. This vibration is of much smaller amplitude than that of the inner cutter with the result that as the razor is drawn down the face there is a movement at right angles to said travel which tends to sift the hair of the beard through the slots 35 of the outer cutter into a position in which they may be more readily cut.

This same sifting action tends to keep the razor constantly in motion thereby preventing the skin from forming ridges which may enter between the cutter bars and be chafed and burned.

While we have described what we consider to be a highly desirable embodiment of our invention, it is obvious that many changes in form could be made without departing from the spirit of our invention.

What we claim as new, and desire to secure by Letters Patent, is.

1. A dry shaving head comprising, a fixed outer cutter, an inner cutter movably mounted therein, vibratory means for oscillating said inner cutter,

said outer cutter having a base portion with a slot therein to permit passage of said vibratory means, and a rubber member positioned at each end of said slot for engaging the free end of said vibratory means near said inner cutter and at the end of the stroke of vibratory motion of said means for limiting the amplitude of vibration and deadening sound.

2. A dry shaver comprising a casing having a compartment therein, an outer cutter having a base portion mounted on said casing at one end, said base portion being formed to provide a slot communicating with the compartment in said casing, an inner cutter reciprocably mounted in said outer cutter, a vibratory member mounted on said casing at the end opposite to said outer cutter and having the free end extending through the slot in said base portion and interengaged with said inner cutter for reciprocating said inner cutter in the vibratory movement thereof, and a cushioning member mounted on said base portion in said slot for contacting the free end portion of said vibratory member near the end of its stroke of vibratory motion whereby the means for vibrating said member may operate thereon at a position intermediate said cushioning member and the opposite end of said casing.

3. A dry shaving head comprising a fixed outer cutter, an inner cutter movably mounted therein, vibratory means having a free end for engaging and oscillating said inner cutter, said outer cutter having a base portion with a slot therein to permit passage of the free end of said vibratory means, and a resilient bushing positioned adjacent said free end portion of said vibratory means and at opposite sides thereof and operable at the end of the stroke of vibratory motion of said means for limiting the amplitude of vibration and deadening sound.
